UNITED STATES PATENT OFFICE.

GEORGE W. McMUNN, OF PITTSBURGH, PENNSYLVANIA.

PROTECTIVE DEVICE FOR RAILWAYS.

1,232,584.

Specification of Letters Patent. Patented July 10, 1917.

Application filed July 28, 1916. Serial No. 111,824.

To all whom it may concern:

Be it known that I, GEORGE W. McMUNN, a citizen of the United States, residing at Pittsburgh, in the county of Allegheny, and 5 State of Pennsylvania, have invented certain new and useful Improvements in Protective Devices for Railways, of which the following is a specification.

My invention relates to improvements in 10 protective devices for railways.

Railroad trains are generally operated under block signal systems which include operator and automatic control. Signal towers are provided at suitable intervals, operators of these towers controlling the signals of the towers. Between these towers the signals are automatic and are controlled by the trains passing through the blocks, each 15 train setting the signals of blocks in rear of the train, as for instance, by setting a signal at the entrance of the block in which the train is located and the signal at the entrance of the block immediately preceding it both at danger position, and placing the signal 20 of the block preceding these blocks in cautionary position. This action is produced through the wiring connections of the blocks, the train forming the controlling agency by connecting the opposite track rails of a block 25 in such manner as to produce this signal operation. As the train proceeds the signals are automatically changed by the train passing from one block to another, preserving, however, the general signal protection in the 30 rear of the train.

While this signal device is sufficient under 35 general operating conditions, circumstances may arise which will make the service ineffective, in which case accidents are liable 40 to occur.

For instance, a train may meet with an accident which tends to more or less obstruct an adjoining track. This would not affect the signal conditions of that track, so 45 that it is necessary for one or more trainmen to attempt to protect that track through manual signaling, necessitating a lengthy run by the trainmen, especially where the running times of trains indicates that an 50 approaching train is in the vicinity of the accident. A similar condition might arise under conditions where an actual blockading of the adjoining track would not take place,

as for instance, where the door of a freight car should become loose and swing outward 55 so as to endanger a passing train.

Another form of danger is where blocks are of short length and a train comes to a stop just beyond the entrance to a block, thus decreasing the signal area as well as the 60 protection afforded by such signal area.

Attempts have been made to overcome these objectionable features by providing an arrangement for temporarily producing rail-bridging action independent of the train, but 65 the constructions of which I am aware are unsatisfactory for various reasons. For instance, they are heavy and cumbersome, making it a laborious operation for the trainmen to carry them to the point of application; they require clamping or adjusting devices to secure them in position; and the parts are generally so connected as to provide a rigid connection between the rails 70 and a fixed projecting structure which extends above the rails.

Aside from the difficulties incident to manipulation, the presence of the portion projecting above the tops of the rails practically prevents the use of such structures in 80 service. This difficulty arises by reason of the particular manner in which trains are controlled by the signals. For instance, the danger position of an automatic signal has a different meaning from that of the tower 85 signal when in the same position. In both cases the train must come to a full stop. When the signal is given at a tower, the train must remain until the signal man permits it to proceed by changing the signal. 90 On the contrary, the automatic signal requires only a stop for a predetermined length of time (generally one minute) after which the train proceeds under the rules governing cautionary signals until reaching 95 a signal which indicates a clear track.

It will be obvious that under such conditions the presence of a temporary device which would itself offer an obstruction to the train may affect train derailment as the 100 train proceeds.

The present invention, while employing the general idea of temporarily connecting rails to affect the signal circuit, is designed more particularly to provide a structure 105 which can be quickly applied to position,

which is of simple construction and of light weight so as to be readily transported, which will present no obstruction to the passage of the train thereover, which can be 5 placed in position regardless of the presence or absence of intervening rails, etc., as where a switch is present, and which can be manufactured at a relatively low cost.

To these and other ends, the nature of 10 which will be readily understood as the invention is hereinafter disclosed, said invention consists in the improved construction and combination of parts hereinafter fully described, illustrated in the accompanying 15 drawings and more particularly pointed out in the appended claims.

In the accompanying drawings, in which similar reference characters indicate similar parts in each of the views;

20 Figure 1 is a diagrammatic sectional view showing the general application of the present invention.

25 Fig. 2 is a vertical sectional view taken through a rail and showing one of the devices of the present invention in position thereon.

Fig. 3 is a plan view of a blank which may be employed in producing the rail-engaging structure.

20 Fig. 4 is a detail view showing a different way of producing rail-engaging fingers.

Fig. 5 is a detail view of a portion of a blank showing a different arrangement for connecting the conductor to the device.

35 Fig. 6 is a sectional view taken on line 6-6 of Fig. 5.

The principal device of the present invention is the rail-engaging member, this member being made of sheet metal and preferably of thin sheet steel. As shown in Fig. 40 2, the member is shaped to practically fit the contour of the top of the rail, and being comparatively thin will offer no obstruction to a passing train so that the latter is not liable to derailment or other damage should 45 the train actually pass over the device.

As shown in Fig. 3 the device may be formed from a blank 10, the blank having any desired contour, that shown in this figure being simple and readily produced by stamping. At a proper point in the length of the blank, the latter may be slit, as at 11, or otherwise manipulated, as to produce fingers 12, this can be readily produced 55 by the action of dies. In Fig. 3 an arrangement of two fingers is shown. In Fig. 4 the slits are arranged to produce a single finger 12.

The blank is shaped in suitable manner, as 60 by dies, to produce an in-turned portion 13 at the outer end, this portion being adapted to engage the under face of the rail-head or the outer side of the rail, the blank then following the contour of the sides and top 65 face of the rail-head and then leading in-

wardly from the inner side of the rail-head in such manner as to contact with the face of the web or of a fish plate, depending upon the point of application of the device. Such web-contacting portion may be arranged in 70 suitable manner, a preferred arrangement being to provide a curved portion which causes the end of the blank to project inwardly, as shown more particularly in Fig. 2, this end being provided with any suitable 75 means by which a conductor can be quickly applied to the device. In Fig. 3 I have shown such device in the form of a slot 14 having converging sides, into which the hooked end of a conductor can be readily 80 passed and quickly drawn into engagement with the walls of the slot. In Figs. 5 and 6 is shown upwardly turned fingers 15 stamped from the blank and about which the conductor may be quickly wrapped. Obviously many other forms of producing an 85 engaging member for the conductor are applicable for use in this connection.

As shown in Fig. 2, the finger or fingers 12 are adapted to engage the under face of 90 the rail-head on the inside of the rail, these fingers and member 13 acting to hold the device in position. As will be readily understood, fingers 12 will yield while the device is being placed in position, but will 95 spring inwardly after the ends of the fingers have reached a point where the resiliency will permit them to spring inward. When in position they form stops to maintain the device in position.

The application of the device to a rail will be readily understood. Member 13 is placed in an approximate position after which the device is simply swung downwardly to its proper position; if necessary, force can be applied by the hand or foot of the trainman in placing it into position. After applying the two devices to the rail-heads of the particular track being controlled, the trainman simply engages the 105 ends of the conductor with the retaining devices of the members. As will be understood the conductor may be flexible or otherwise and is preferably of a length greater than the distance between the rails, thus enabling application of the structure to points where a switch rail may be present between the rails of the track, the conductor simply passing underneath the intervening rail.

The ability to use flexible or other simple 110 form of conductor is due to the fact that the rail engaging devices are not dependent on the conductor or connection in maintaining the devices in position on the rails, the particular form of each device being such that 115 its engagement with the rail firmly positions the device on the rail and does not require the presence of a connecting member for providing such support.

This latter fact enables the device to be 130

used for other purposes than the one herein mentioned. For instance the device may be employed for the purpose of retaining the ordinary signal cap or torpedo on the rail, 5 the holding bands of the latter simply slipping between the device and the face of the rail.

While I have shown the inner portion of the device as being bent inwardly to extend 10 into contact with the rail (an arrangement which increases the contact surfaces of rail and device to insure proper electric connection), I do not limit the construction in this respect since contact with the web of the 15 rail is not essential, so that the portion below the fingers may have other configurations, as for instance extending downwardly in the plane of the portion which contacts with the inner face of the rail-head, the essential 20 being that fingers, such as indicated at 12, or an equivalent structure, will contact with the under face of the rail-head when the device is in position.

As will be readily understood from the disclosure of Fig. 2, not only is there no material obstruction provided at the top of the rail, but in addition, no material obstruction 25 is placed in the path of travel of the wheel flange.

30 In fact, should it be found desirable, the inner end of the device may be formed in a way to bring the conductor or connection into the path of travel of a wheel flange thus causing the first passing train to break the 35 connection through severing the conductor or breaking the connection between the conductor and the device, thus rendering the structure inoperative for further signaling purposes, this action being provided by the 40 movement of the train itself without liability to cause accidents. Such an arrangement is considered as falling within the scope of the present invention.

Not only is the device simple and efficient 45 in application and in operation, but it is in such form as can be carried by a trainman without difficulty. It is necessary only to carry a pair of the devices and a conductor of suitable length to complete the apparatus. 50 Each device is comparatively small and of light weight so that no bulky or cumbersome apparatus is present.

Obviously the cost of manufacture is low, the device, in any of the forms shown, being 55 one which can be readily produced by machinery of simple type.

While I have herein shown and described one or more ways in which my invention may be carried into effect, it will be readily 60 understood that variations and modifications therein may be required or desired to meet individual conditions of use, and I desire to be understood as reserving the right to make any and all such changes and modifications as may be found desirable or re-

quired, in so far as the same may fall within the spirit and scope of the invention as pointed out in the accompanying claims.

Having thus described my invention, what I claim as new is—

1. A device adapted for use in railway protection comprising a sheet metal member formed to attachably embrace a rail-head in a manner to permit passage of rolling stock thereover and having means for the attachment thereto of a conductor. 75

2. A device adapted for use in manually controlling the actuation of track signals for railway protection comprising a sheet metal member shaped to correspond approximately 80 with the sides and tread face of a rail-head, said member having means to engage the under face of the rail-head on opposite sides of the rail web.

3. A device adapted for use in manually controlling the actuation of track signals for railway protection comprising a sheet metal member shaped to correspond approximately 85 with the sides and tread face of a rail-head, said member having means to engage the under face of the rail-head on opposite sides 90 of the rail web, said means including a resilient element adapted to yield during the positioning movements of the member.

4. A device adapted for use in railway 95 protection comprising a sheet metal member shaped to correspond approximately with the sides and tread face of a rail-head, said member having means to engage the under face of the rail-head on opposite sides of 100 the rail web, said member also having means for the attachment of a conductor thereto below the plane of the rail tread face.

5. A device adapted for use in railway protection comprising a sheet metal member 105 shaped to correspond approximately with the sides and tread face of a rail-head, said member having means to engage the under face of the rail-head on opposite sides of the rail web, said means including a resilient 110 element adapted to yield during the positioning movements of the member, said member also having means for the attachment of a conductor thereto below the plane 115 of the rail tread face.

6. A device adapted for use in manually controlling the actuation of track signals for railway protection comprising a sheet metal blank bent to correspond approximately 120 with the side and tread faces of a rail-head and having one end bent to engage an under face of said head, said blank carrying integral means adapted to engage the under face of the head on the opposite side of the rail web.

7. A device adapted for use in manually controlling the actuation of track signals for railway protection comprising a sheet metal blank bent to correspond approximately 125 with the side and tread faces of a rail-head 130

- and having one end bent to engage an under face of said head, said blank carrying integral resilient means adapted to engage the under face of the head on the opposite side 5 of the rail web, said resilient means being adapted to yield during the positioning movements of the device and form a stop to maintain contact of rail and device when positioned.
10. 8. A device adapted for use in railway protection comprising a sheet metal blank bent to correspond approximately with the side and tread faces of a rail-head and having one end bent to engage an under face of 15 said head, said blank carrying integral resilient means adapted to engage the under face of the head on the opposite side of the rail web, said resilient means being adapted to yield during the positioning movements 20 of the device and form a stop to maintain contact of rail and device when positioned, said device having means beyond said resilient means for the attachment of a conductor to the device.
25. 9. The combination with the rails of a track under block signal control, of a temporary control device adapted to operate track signals, said device comprising a pair of independent members each adapted to at- 30 tachably embrace a rail-head in a manner to permit passage of rolling stock thereover and a conductor adapted to be attached to said members and forming the sole connection therebetween.
35. 10. The combination with the rails of a track under block signal control, of a temporary control device adapted to operate track signals, said device comprising a pair of independent members each adapted to at- 40 tachably embrace a rail-head in a manner to permit passage of rolling stock thereover and a conductor adapted to be attached to

said members and forming the sole connection therebetween, said members and conductor having complementary formations to 45 permit of rapid completion of the connection.

11. The combination with the rails of a track under block signal control, of a temporary control device adapted to operate 50 track signals, said device comprising a pair of independent sheet metal members of similar configuration and each adapted to embrace a rail-head in a manner to permit passage of rolling stock thereover, said members each having means to attachably receive a conductor to connect said members, the means of the members being located on the inner side of each rail below the tread face, whereby the conductor may be located 60 below the plane of the tread face of the rails.

12. The combination with the rails of a track under block signal control, of a temporary control device adapted to operate 65 track signals, said device comprising a pair of independent sheet metal members of similar configuration and each adapted to embrace a rail-head in a manner to permit passage of rolling stock thereover, said members each having means to attachably receive a conductor to connect said members, the means of the members being located on the inner side of each rail below the tread face, whereby the conductor may be located below 70 the plane of the tread faces of the rails, said members being free from connection other than the connection provided by the conductor.

In testimony whereof I affix my signature 75
in presence of a witness.

GEORGE W. McMUNN.
